ELECTRICAL COUNTING SYSTEM

Thomas L. Dimond, Boonton, N. J., assignor to
 Bell Telephone Laboratories, Incorporated, New
 York, N. Y., a corporation of New York

Application January 20, 1934, Serial No. 707,474

9 Claims. (Cl. 179—16)

This invention relates to electrical pulse storing systems and its object is to secure improvements in storing and repeating electrical impulses.

5 In the applicant's copending application, Serial No. 707,471, filed Jan. 20, 1934, a system has been provided for counting and denoting the number of operations of contacts, the arrangement being such that a neon lamp or similar discharge device is included in a circuit in which a first condenser is charged from a source of energy under control of contacts and a second condenser is charged from the first condenser under control of said contacts. These operations 10 are repeated until the second condenser has accumulated a charge equal to the breakdown potential of the discharge device in series with the second condenser, the breakdown of the device indicating that the contacts have operated a certain number of times.

It is a feature of the present invention to store impulses and count them out or repeat said impulses through circuit arrangements making use of condensers and contact arrangements as disclosed in the above mentioned copending application. The arrangement in the present case comprises a discharge device of the three-element type, an input circuit including the grid, two condensers and contacts, one condenser being charged from the other through the operation of the contacts and an output circuit including the filament, two condensers and contacts in which one condenser is charged from the other due to the operation of these latter contacts. The circuit connections are such that the grid normally has a negative bias with respect to the filament due to a slight drop through resistance in the filament circuit. This bias is sufficient to prevent breakdown through the flow of plate current in the tube. When the contacts in the input circuit are operated by incoming impulses to be stored, a first condenser in the input circuit is charged in increments from a second condenser to a point depending on the number of impulses received. The rise in voltage across this first condenser does not cause the tube to break down since the grid becomes more negative with respect to the filament. The impulses thus stored on the first condenser in the input circuit may be counted out or repeated through the output circuit by the operation of the contacts therein, which in operating charge a first condenser from a second condenser in the same small increments until the first condenser has received the same charge

as was stored on the first condenser in the input circuit. In the meantime or prior to the repeating of the impulses the bias between the filament and grid is slightly decreased by the operation of a key to short circuit a resistance in the filament circuit. This will not have any immediate effect on the tube to cause it to break down as the bias was materially increased by the charge on the first condenser in the input circuit. When, however, the first condenser in the output circuit has reached practically the same potential as on the first condenser in the input circuit the tube will break down to cause a current to flow through the plate circuit to operate a relay therein to indicate that the stored impulses have been repeated by the output circuit. A modified form of this invention is an arrangement of circuits similar to those outlined above, whereby the potential on the filament is varied instead of the grid potential to accomplish the same result.

Another feature of this invention is that this circuit arrangement includes a common source of current and therefore operates independently of the value of the applied voltage used in operating the device within reasonable limits since the voltages to which the condensers in both the input and output circuits are charged for any particular number of impulses are each proportional to the applied voltage.

The invention has been illustrated in the accompanying drawing in which:

Fig. 1 shows the invention applied to a three-element tube of the thyratron type;

Fig. 2 shows a similar arrangement with the input and output circuits reversed; while

Fig. 3 shows a modification of Fig. 1.

Referring to Fig. 1 the tube 1 comprises a plate, a filament and a grid. The input circuit in this case includes the grid and a condenser 2 while a charging means for the condenser 2 in increments comprises an input relay 3 or other suitable device for operating contacts 4 to charge the condenser 2 from condenser 5 which receives charges from the battery and ground 6. Similarly, in the output circuit is included the condenser 10 to be charged in steps from condenser 11 controlled by an output relay 12 through contacts 15 and battery 14. A key 15 is provided to short-circuit a resistance 16 controlling the operation of the device as will hereinafter be described.

The operation of the system disclosed in Fig. 1 is as follows: The input relay 3 may receive im-

5 pulses of different digits to be stored. Each digit will charge the condenser 2 correspondingly. When relay 3 is operated in response to an impulse a portion of the charge normally accumulated on condenser 5 from battery 6 will be transferred to the condenser 2 and when relay 3 is released condenser 5 will be recharged. This process is repeated until the desired number of impulses have been stored as represented by increments of charges on condenser 2. As the condensers 2 and 10 are normally completely discharged and due to the presence of the resistances 16, 17 and 18 in the filament circuit the potential on the grid will be the same as that of the negative side of the battery 6, since there is no voltage drop across either the condenser 2 or 10, while the filament will have a positive bias with respect to the grid on account of the IR drop through resistances 16 and 17. This grid bias is just sufficient to prevent the breakdown or flow of current through the tube. The potential on condenser 2 applied by the impulses as described will therefore not cause the tube to break down since the grid has merely become more negative with respect to the filament.

10 The digit represented by the charge on the condenser 2 may be repeated or counted out by the operation of the output relay 12. To accomplish this the contacts 15 must first be operated to short-circuit resistance 16, in order to slightly reduce the positive bias on the filament. The tube will, of course, not break down at this time due to the grid having been made highly negative with respect to the filament by the charge on condenser 2. The alternate operation and release of the output relay 12 will now charge the condenser 10 in steps from condenser 11 in the same manner as condenser 2 was charged from condenser 5. As the ratio between 15 the capacities of condensers 11 and 10 is the same as that between the capacities of condensers 5 and 2, the voltage across condenser 10 will be equal to that across condenser 2 when the output relay 12 has operated the same number of 20 times as the input relay 3. Since these voltages are opposing in the circuit from the negative side of battery 14 to the grid, the grid is now at exactly the same potential as the negative side of battery 14 or, in other words, it is at the same 25 potential it was before any pulses were stored. However, since the grid bias was changed by the operation of contacts 15, the tube will now break down and cause the control relay 19 in the plate 30 circuit to operate. The control relay 19 may be employed to prevent further impulses from being transmitted by the output relay and cause it to discontinue to function in any suitable manner in the circuit and it may also be used to indicate that a certain number of impulses has been 35 stored and repeated. It is evident that this system may be used for storing and repeating succeeding series of impulses. The only actions required between the storing of the digits are to open the plate circuit to release 19 which may be done by the opening of contacts 20 and to restore key 15 to normal and to discharge the condensers 2 and 10.

40 In Fig. 2 the same type of thyratron tube 1 is employed and the circuits are similar except that the filament is included in the input circuit and the grid in the output circuit. The input relay 21 in this case will operate to alternately charge condenser 22 from condenser 23 by the operation of its contacts, and the output relay 24 will

5 operate to alternately charge condenser 25 from condenser 26 by the operation of its contacts. As the condensers 22 and 24 are normally fully discharged the voltage drop across each of them is zero. For this reason, the grid will assume normally the same potential as the negative side of the battery 27. The filament will have a potential the same as that at the connecting point between resistances 28 and 29. Since this point is positive with respect to the negative side of the battery 27, the filament will be positive with respect to the grid and resistances 28, 29 and 30 may be such that the tube will be blocked or prevented from breaking down. After the charge on condenser 22 has been increased by the operation of relay 21 to store a desired number of impulses, contact 31 will be operated to shunt resistance 30 to make the filament slightly less positive in respect to the grid. The output relay 24 may then start to operate and alternately charge condenser 25 in steps from condenser 26 by the operation of its contacts in the same manner as condenser 22 was charged from condenser 23 in the input circuit. When the output relay 24 has operated the same number of times as the 15 input relay 21 the voltage across condenser 25 will be the same as that across condenser 22 assuming, of course, that the same ratio exists between the capacities of condensers 22 and 23, as between 25 and 26. The grid will now be at 20 the same potential as the filament except for the slight biasing voltage drop through resistance 29. Since this bias is not sufficient to block the tube it will pass plate current through battery 34, the control relay 35 and the plate circuit. The control relay 35 may be used for the same purpose as control relay 19, for example, to prevent further operation of output relay 24 to transmit further impulses. The function of the potentiometer arrangement of resistances 36 and 37 35 to ground in the circuit for the condenser 26 is to provide the same charging voltage for condenser 25 as for condenser 23.

40 Both of the circuits shown in Figs. 1 and 2 are practically independent of applied voltages within reasonable limits since the voltages to which both the charged condensers 2 and 10 in Fig. 1 and 22 and 25 in Fig. 2 for a certain number of impulses are each proportional to the applied voltage.

45 It is evident that this invention may be applied to other modified circuit arrangements, such as, for example, where several succeeding digits may be stored in succeeding condensers corresponding to condensers 2 or 22 and coupled to the input circuit and then counted out at will. In such cases, the condensers used for storing the pulses need not be directly connected in the input circuit until the digits stored in the same 50 are to be counted out. Consequently, the same tube may be used with several storing condensers 55 corresponding to condensers 2 and 22, each of which may be independently charged by a circuit similar to the input circuits and later connected in proper sequence to the tube and associated output circuit.

60 Such a circuit has been shown in Fig. 3 which is in all other respects similar to Fig. 1. In this figure two storing condensers 40 and 41 have been shown. These condensers may be connected individually through contact 42 for condenser 40 and contact 43 for condenser 41 to the contacts of the input relay 3 and charged independently by any desired series of impulses as controlled by relay 3 and condenser 5. Later the condensers 70 65

40 and 41 may be connected individually in sequence through contact 44 for condenser 40 and contact 45 for condenser 41 to the input circuit of the tube 1 for repeating of the succeeding series 5 of impulses to the output circuit. It should be noted that the contact 15 used in Fig. 1 to short-circuit resistance 16 is not required in this case as when condenser 40 or 41 is connected to the input circuit it is always charged sufficiently to 10 block the tube from breaking down. A similar arrangement may be provided for the input circuit of the arrangement shown in Fig. 2.

What is claimed is:

1. In combination, a conduction device having 15 a filament, grid and plate, means for normally maintaining a difference between the potentials on the filament and on the grid sufficient to prevent the breakdown of the device, means for changing the potential on a first one of said two 20 elements in steps to increase the potential difference between said elements, means for slightly decreasing said established potential difference between said two elements, and means for changing the potential on said first element in the 25 same number of steps to decrease said established potential difference to a point where said device breaks down.

2. In combination, a conduction device having a filament, a grid and a plate, means for normally maintaining a negative bias on the grid with respect to the filament sufficient to prevent the breakdown of the device, means for increasing said bias by changing the potential in varying numbers of steps on the grid, means for decreasing said bias by changing the potential on the filament, and means for eliminating said bias by changing the potential on the grid in the same 30 number of steps to cause the device to break down at various potentials corresponding to the 40 number of steps at which the potentials were changed.

3. In combination, a conduction device having a filament, a grid and a plate, means for normally maintaining a difference between the potentials on the filament and on the grid sufficient to prevent the breakdown of the device, means for changing the potential on said elements to cause the breakdown of the device including the change in potential on one element in a certain number of steps, the change of potential on the other of said elements in a single step followed by the change of potential on the first mentioned of said elements in the same number of steps as the potential on said first mentioned 55 element was originally changed.

4. In combination, a conduction device having a filament, a grid and a plate, means for normally maintaining a negative bias on the grid with respect to the filament sufficient to prevent the breakdown of the device, means for increasing the negative bias on the grid, means for decreasing the positive bias on the filament, and a separate means for thereafter decreasing the negative bias on the grid to the point where the device breaks down.

5. In combination, a conduction device having a filament, a grid and a plate, an input circuit including a condenser and the grid, an output circuit including a condenser and the filament, 70 means in said circuits for establishing a positive bias on the filament with respect to the grid, means for charging the condenser in the input circuit in small increments at intervals to establish corresponding potentials on the grid to make the grid more negative with respect to the fila-

ment, means in the output circuit for making the filament slightly less positive with respect to the established grid potential, and means for charging with the same small increments the condenser in the output circuit in the same manner as the charging of the condenser in the input circuit to establish a potential on the grid of the same value as that established on the filament to cause the breakdown of said device at said potentials and a plate circuit for the passage of plate 10 current when said device breaks down.

6. In combination, a conduction device having a filament, a grid and a plate, an input circuit including a condenser and a grid, an output circuit including a condenser and a filament, a common source of current for said circuits, means in said circuits and including said source for normally maintaining a potential difference between the grid and filament to prevent the breakdown of the device, means for charging the condenser in the input circuit in varying numbers of steps to establish corresponding potentials on the grid making the grid potential more negative with respect to the filament potential, a key in the output circuit, means controlled by the operation of said key for making the filament potential slightly less positive with respect to the established grid potential, means for charging the condenser in the output circuit in corresponding numbers of steps to establish a potential on the grid of the same value as the potential established on the filament to cause the breakdown of said device at said corresponding potentials.

7. In combination, a conduction device having a filament, a grid and a plate, an input circuit including a condenser and a grid, an output circuit including a condenser and the filament, means in said circuits for establishing a potential difference between said grid and filament with a positive bias on the filament with respect to the grid, means including a third condenser for charging the condenser in the input circuit in small increments from said third condenser at intervals to establish corresponding potentials on the grid making the grid more negative with respect to the filament, means in the output circuit for making the filament potential slightly less positive with respect to the established grid potential, and means including a fourth condenser for charging the condenser in the output circuit in the same small increments from said fourth condenser at intervals an equal number of times as the condenser was charged in the input circuit to establish a potential on the grid to cause the breakdown of said device.

8. In combination, a conduction device having a filament, a grid and a plate, means for normally maintaining a negative bias on the grid with respect to the filament, means for changing the potential on the filament in steps to increase the positive bias on the filament with respect to the grid, means for thereafter slightly decreasing said positive bias on the filament, and means for thereafter changing the potential on the filament in an equal number of steps to make it sufficiently less positive with respect to the established grid potential to cause the breakdown of the device.

9. In combination, a conduction device having a filament, a grid and a plate, an input circuit including a condenser and the filament, an output circuit including a condenser and the grid, means in said circuits for establishing a potential difference between said grid and filament with a negative bias on the grid with respect to the filament, means for charging the condenser in the input circuit in small increments at intervals to establish corresponding potentials on the grid to make the grid more negative with respect to the fila-

input circuit in steps to establish corresponding potentials on the filament to make the positive bias greater on the filament with respect to the grid, means for decreasing said positive bias on the filament to a small degree, and means for charging the condenser in the output circuit in an

equal number of steps to those at which the condenser in the input circuit was charged to decrease the positive bias of the filament to cause the breakdown of the device.

THOMAS L. DIMOND.
